(57) **CLAIM**

The ornamental design for a fan clip, as shown and described.

DESCRIPTION

FIG. 1 is a top view of a fan clip showing my new design;
FIG. 2 is a bottom view thereof;
FIG. 3 is a front view thereof;
FIG. 4 is a rear view thereof;
FIG. 5 is a left side elevational view thereof;
FIG. 6 is a right side elevational view thereof; and,
FIG. 7 is a perspective view thereof.

The area between the dot-dash lines in FIG. 1 depict a portion of the fan clip that form no part of the claimed design. The areas within the dot-dot-dash line in FIGS. 6 and 7 depict portions of the fan clip that form no part of the claimed design.

1 Claim, 7 Drawing Sheets
